UNITED STATES PATENT OFFICE.

JOHN EDWARD WEST, OF FORTESCUE, MISSOURI.

CHUTE-VALVE CONTROL.

Application filed November 1, 1919. Serial No. 334,927.

To all whom it may concern:

Be it known that I, JOHN EDWARD WEST, a citizen of the United States, residing at Fortescue, in the county of Holt and State 5 of Missouri, have invented certain new and useful Improvements in Chute-Valve Control, of which the following is a specification, reference being had to the accompanying drawings.

10 This invention relates to certain improvements in grain elevators, and has relation more particularly to a device of this general character wherein a vertical movable valve or gate is employed to control the flow 15 over a chute leading from the grain bin to the boot of the elevator, and it is an object of the invention to provide a novel and improved means whereby the gate or valve may be conveniently and effectively locked 20 in its different positions.

Another object to the invention is to provide a gate or valve for the grain chute provided with an upstanding gate or operating valve, and with which coacts a novel and 25 improved locking means embodying a holding member constantly urged in a direction for working engagement with the rod, together with means for moving the holding member away from the rod so that the gate 30 or valve may be adjusted without interference by said holding member.

Another object of the invention is to provide a novel and improved mechanism coacting 35 with the valve or operating rod for locking the valve or gate in desired position, together with means carried by the rod for limiting the upward or opening movement of the valve or gate.

The invention consists in the details of 40 construction and in the combination and arrangement of the several parts of my improved grain elevator whereby certain important advantages are attained and the device rendered simpler, less expensive and 45 otherwise more convenient and advantageous for use, as will be hereinafter more fully set forth.

The novel features of my invention will 50 hereinafter be definitely claimed.

55 In order that my invention may be the better understood, I will now proceed to describe the same with reference to the accompanying drawings, wherein:

Figure 1 is a fragmentary view partly in 55 section and partly in elevation illustrating a vertically movable valve or gate for grain

elevators, and illustrating an embodiment of my invention, as herein disclosed;

Figure 2 is an enlarged fragmentary view partly in elevation, illustrating in detail my 60 improved holding means coacting with the operating rod;

Figure 3 is a sectional view taken substantially on the line 3-3 of Figure 2,

Figure 4 is a fragmentary sectional view 65 taken substantially on the line 4-4 of Figure 2, and

Figure 5 is a plan view of the lock casting.

As disclosed in the accompanying drawings, F denotes a flooring arranged in a conventional manner over the point P of a grain elevator, and in which point is arranged the boot B of the elevator of a conventional type. G denotes a grain bin from 75 which leads a chute C delivering to the boot B.

V denotes a vertically movable valve or gate for controlling the flow of the grain from the bin G over the chute C and extending upwardly from the valve or gate V is the rod R. The upper end of the rod R is provided with a hand hold H whereby the rod R may be manually operated to vertically move the valve or gate V in accordance 85 with the requirements of practice.

1 denotes a casing provided at its top with laterally directed flanges 2, whereby the casing can be readily anchored to the upper surface of the flooring F. The upper and 90 lower walls of the casing 1 are provided with the vertically aligned openings 3 through which the rod R is directed, and whereby said rod R vertically intersects the casing 1.

Pivots supported, as at 5, within the casing 1, and to one side of the rod R is a holding or locking dog D, which has swinging movement toward or from the rod R and the working face or edge of said dog D is 100 provided with a groove 6 to receive the rod R when the dog D is in locking engagement with said rod. The wall of the groove 6 is provided with the recesses 7 or the like, whereby the gripping action of the dog up- 105 on the rod R is materially facilitated.

The dog D is constantly urged downwardly toward the rod R through the medium of the spring 9, and said spring is of sufficient tension to lock the rod R normally 110 against movement so that the valve or gate V may be effectively locked in its different

positions as the requirements of practice may necessitate.

The pivoted portion of the dog D is provided with the tail 10 with which contacts the lower end of a vertically disposed shank or releasing member 12. The member 12 extends upwardly through an opening 14 in the top of the casing 1, and through an opening 15 in the flooring F and in register with said opening 14. The shank or release member 12 has its upper end terminating a desired distance above the flooring F, and is provided with the head 16. Upon depression of the shank or release member 12, which may be accomplished by a foot or otherwise, the dog D will be swung about its pivot in a direction away from the rod R so that desired endwise movement may be imparted to the rod R to obtain the desired 20 positioning of the valve or gate V. Upon relieving the shank or member 12 of pressure, the spring 9 will cause the dog D to automatically grip and lock the rod R. It is to be understood that the spring 9 is also of sufficient tension to readily overcome the weight of the shank or release member 12.

Carried by the rod R at a desired point below the casing 1 is a stop member M, which by engagement with the casing 1, serves to limit the upward movement of the valve or gate V, so that displacement of said valve or gate V with respect to the chute C is prevented.

As herein disclosed the member M comprises two duplicate parts 16, having their central portions 17 provided with outbows adapted to embrace the rod R, and said

parts 16 are clamped to the rod R through the medium of the bolts 18 or the like. In order to increase the gripping action of the parts 16 upon the rod R, the inner or contacting face of the outbows 17 are grooved or otherwise roughened, as at 19.

From the foregoing description it is thought to be obvious that a grain elevator constructed in accordance with my invention is particularly well adapted for use by reason of the convenience and facility with which it may be assembled and operated and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

A chute valve control comprising a casing, a valve operating rod mounted to reciprocate vertically therein, a locking dog pivoted in the casing and having a serrated cam-shaped rod engaging face, a spring normally acting to force the dog into locking engagement with the rod, and a vertically movable plunger slidably mounted in the casing and adapted to release the locking dog, said dog being adapted to lock the rod in any adjustable position, together with means to prevent displacement of the valve.

In testimony whereof I hereunto affix my signature.

JOHN EDWARD WEST.
